UNITED STATES PATENT OFFICE

102,222

DESIGN FOR AN EMBROIDERED NET

Jack J. Blackstone, New York, N. Y.

Application November 5, 1936, Serial No. 65,711

Term of patent 3½ years

To all whom it may concern:

Be it known that I, Jack J. Blackstone, a citizen of the United States of America, residing in city of New York, county of New York, and State of New York, have invented a new, original, and ornamental Design for an Embroidered Net of which the following is a specification, reference being had to the accompanying drawing, forming part thereof,

The figure of the drawing is a plan view of an embroidered net showing my new design.

I claim:

The ornamental design for an embroidered net substantially as shown.

JACK J. BLACKSTONE.
